UNITED STATES PATENT OFFICE.

ISAAC N. GLAUBER, OF CLEVELAND, OHIO.

DESIGN FOR A HANDLE FOR WATER COCKS AND VALVES.

SPECIFICATION forming part of Design No. 33,861, dated January 8, 1901.

Application filed December 10, 1900. Serial No. 39,442. Term of patent 7 years.

To all whom it may concern:

Be it known that I, ISAAC N. GLAUBER, a citizen of the United States, residing at Cleveland, in the county of Cuyahoga and State of Ohio, have invented and produced a new and original Design for Handles for Water Cocks and Valves, of which the following is a specification, reference being had to the accompanying drawings, forming part thereof.

Figure 1 is a plan view of a handle of the kind described embodying my new design, and Fig. 2 is an edge view thereof.

As thus shown, the leading or material feature of my design consists in the shape or outline of the said handle, the same being distinguished from others and marked especially by a rim having opposite flat smooth surfaces 2 and a wavy or scalloped edge 3, a central circular ornamentation 4, of hub shape, extending outward on both sides beyond the

adjacent surfaces and relieved by an opening 5 through its center, while the intermediate surfaces 7 on both sides of the design between rim 2 and central ornamentation 4 are retired or sunk beneath the surfaces 2, substantially as shown, thus subordinating these retired features and making especially conspicuous the rim 2 and the central projections 4 of the design.

What I claim is—

The design for a handle for water cocks and valves, substantially as herein shown and described.

Witness my hand to the foregoing specification this 4th day of December, 1900.

ISAAC N. GLAUBER.

Witnesses:

M. A. SHEEHAN,
R. B. MOSER.
